UNITED STATES PATENT OFFICE.

CHARLES E. HOPKINS, OF TAUNTON, MASSACHUSETTS.

MACHINE FOR MAKING STEREOTYPE PRINTING-PLATES.

1,268,463.

Specification of Letters Patent.

Patented June 4, 1918.

Application filed February 23, 1912. Serial No. 679,358.

To all whom it may concern:

Be it known that I, CHARLES E. HOPKINS, a citizen of the United States, residing at Taunton, in the county of Bristol and State 5 of Massachusetts, have invented a new and useful Machine for Making Stereotype Printing-Plates, of which the following is a specification.

The principal object of this invention is 10 to provide a plant or combination of machines for more economically producing finished stereotype printing plates than has been possible in the past. It is well known that the stereotype casting boxes require, 15 and must always require, a certain amount of time for permitting the plate cast therein to set, so that it will retain its shape when discharged from the casting box and conveyed to the devices for performing subsequent operations. On the other hand the 20 finishing machine can operate rapidly without waiting for any change in the condition of the metal.

This invention is designed to take advantage of this fact for producing stereotype plates at a very rapid rate and involves the use of a plurality of casting boxes for a single finishing mechanism. The invention also involves the provision of a novel receiver for receiving plates from each of the casting boxes in position to discharge them into the finishing mechanism in a direct path; new devices for transferring the plates from the casting boxes on either side 30 into the receiver, and other improvements in various features of construction for the purpose of carrying forward the general objects of the invention stated above.

Reference is to be had to the accompanying drawings in which:

Figure 1 is a plan of a stereotype plate making plant constructed in accordance with this invention.

Fig. 2 is a side elevation thereof showing 45 the rear casting box in closed position and the front one open.

Fig. 3 is an end elevation thereof showing the locking devices for the two casting boxes in different positions.

Fig. 4 is a sectional view on the line 4—4 of Fig. 2 showing the end of the casting boxes and receiver opposite that shown in Fig. 3.

Fig. 5 is an end view of the receiver and

casting boxes similar to Fig. 4 omitting certain details of construction and the supporting parts.

Fig. 6 is an end view of a casting box on an enlarged scale, with parts broken away, showing the top end of the plate section.

Fig. 7 is a plan of the bottom end of the casting box with a plate and matrix therein and the other end broken away.

Fig. 8 is a side view of one end of the machine with one box ready to be locked in casting position, and

Fig. 9 is a similar view with the parts locked.

Referring first to Figs. 1 and 2 it will be seen that the invention is shown in a form 70 in which a pair of casting boxes A and B are mounted parallel with each other and on opposite sides of a receiver C which is in alignment with a finishing mechanism D and a cooling mechanism E. The casting boxes, receiver and finishing mechanism are shown on an incline so that the plates can be fed down by gravity through the receiver and finishing mechanism and out of the same. This feature is not an element of 80 this invention but is illustrated as showing a convenient type of finishing and feeding mechanism to which this invention can be applied. The objects of this inclined arrangement and the details of the 85 mechanism for securing it will not be gone into herein because they are fully set forth in my co-pending application for patent Serial No. 610,843 filed February 25, 1911, for a machine for making stereotype printing plates.

These parts are shown as mounted on a frame work comprising two parts F and G, the part G supporting the finishing and cooling mechanism. These parts of the 95 frame also are shown similar to others which have been employed heretofore. Each casting box comprises a movable segmental back 8 and a fixed upright core 9.

The frame F is shown as provided with 100 tracks or guides 10 which have horizontal parts and forwardly inclined parts and with another set of tracks or guides 11 which are inclined from a point near the center of the tracks 10 to the bottom of the 105 frame. These tracks or guides are designed to support rollers 12 and 13 respectively and to guide them in proper position.

These rollers are mounted on the segmental backs of the two casting boxes A and B respectively to support them. The motions of the backs to bring them from vertical casting position to the inclined delivering position as shown in Fig. 2 are well understood in this art. An ordinary handle latch 15 is shown for engaging the axle of one of the rollers and holding the back in delivering position.

For the purpose of locking each back in vertical casting position a pair of vertically sliding locking bars 17 are shown. These are provided with vertical slots 18 movable over rollers 19 on studs 20 near the top and bottom of the rear end of the frame. On the upper studs 20 operating handles 21 are pivoted having toggles 22 connected with the bar 17 at a point below the top frame whereby when a handle is moved from the position shown in Fig. 8 to that shown in Fig. 9, the locking bar will be positively lowered and locked in position by the action of the toggles 22. A pair of cam slots 23 and 24 are located in inclined position so that after the back has been brought up into the vertical position shown in Fig. 8 the lowering of the bar 17 will cause these cam slots to pass down over two pairs of studs 25 and 26. The studs 25 are mounted on the edge of the back while the studs 26 are mounted on the side bars 27 of the plate carrying frame, which also comprises end rings 33, a bevel half ring 34, a tail sheet 29, and clamps 30 for the matrix M. When the backs are turned to vertical position facing the cores the studs 25 and 26 are positioned so as to be in the path of the cam grooves and when the locking devices are forced down by pushing up on handles 21 the cams engage and draw forward the backs and plate frames and lock them in casting position against the cores. A bar 28 is fixed to the straight back side of each core near the top to prevent the back from advancing too far, the bottom being taken care of in similar manner by the bevel ring 34 engaging the core face.

The plate carrying frame is pivotally mounted on the back on a shaft 35. The matrix clamps 30 are provided with operating handles 32. A spring 31 is provided in each case for holding these movable parts either in the closed or open position as indicated on the two sides of Fig. 6. When in closed position these bars not only hold the edges of the matrix but they limit and define the edges of the casting chamber.

The shaft 35 for the plate carrying frame has an arm 36 carrying a pin 37. The casting box at the left of Fig. 4 is shown with the back and plate carrying frame in the position assumed when they have been moved up to substantially horizontal position from the casting position. On the

right side of Fig. 4 the back has also been moved up to this position, but the plate carrying frame has been swung upwardly by means of the handle 38 on one of the end rings thereof, and into engagement with the receiver C.

As has been stated there is a receiver C located between the two casting boxes having a central shaft 39 parallel with their axes. This shaft is mounted in bearings 75 on standards 40 and 41 between the two segmental backs. The shaft 39 has oppositely extending arms 43 on the ends of which are mounted flanged rollers 44. These rollers are designed for receiving the cast plate H and feeding it forward as will be seen hereinafter. To one end of the shaft 39 is fastened a bracket 45 carrying a roller 46. This roller is caused to operate in a V-shaped cam plate 47 which is fixed to the end of a vertical rod 48. This rod is supported in a vertical position by bearings on the standard 40 and is normally held up resiliently by a compression spring 49. This spring forces the cam plate up against the roller 46 so as normally to hold the roller in central position and thus hold the whole receiver frame in central horizontal position as shown in Fig. 5.

Attached by studs to a bracket 50^a on the shaft 39 are a set of hanging arms 50 which depend freely from their supports and come against studs 51 on the bracket to limit their inward motion. The lower ends of these arms are formed as hooks 52 turned outwardly. It will be seen therefore that the receiver is normally held in neutral position by spring pressure, but that it can be swung or tilted to either side. This is accomplished by the operation of swinging the plate carrying frame on its pivot away from the back. This motion is a pivotal one about the shaft 39 and it causes the pin 37 to engage in one of the hooks 52 and thereafter causes the receiver to tilt into the position shown in Fig. 4 for receiving the plate and the frame on which it is held. Having transferred the plate to the receiver the frame is swung back and the plate now rests on the receiver. The springs 49 will act on the cam plate and roller to restore the receiver to the neutral position shown in Fig. 5. In this position the plate rests on the rollers 44 which are free to rotate so that the plate can slide down the incline into the finishing apparatus. In order to prevent the plate from starting to slide down the incline before the receiver is in registration with the finishing means the plate is cast with a lug 8 on each side, one of which is adapted to remain in contact with a projection 54 formed on the receiver standard 40 until the receiver comes into neutral position as indicated in Fig. 4. Here the right hand lug 8 is behind the projection 54 on that side 130

and prevents the plate sliding down until the plate gets into the position shown in Fig. 5 where both lugs escape the projection. By this time the lug moves beyond this projection and then the plate is free to slide down into the finishing machine.

The trip lever 259 shown in my above patent application is illustrated herein as applied to each of the casting box supports in position to be operated conveniently by the operator, for the purpose of operating the rod 258 and turning the trip shaft 257 to start the finishing mechanism. The finishing mechanism is shown as provided with operating devices which will not be described further hereinafter as they are fully illustrated and described in my prior application for patent above identified.

The operation of the device is very simple. In order to bring either one of the backs into position for receiving the metal the operator on that side of the machine releases the latch 15 which allows that end of the segmental back to run down the tracks 10. A sufficient momentum is gained by this motion to cause the rolls on the other end to move up the tracks 10 until the back comes into contact with the fixed core. Then the locking cam is operated by moving the handle 21 as has been described heretofore. The casting box is now ready for the metal to be poured and after it is cooled the back is unlocked by reversing the position of the handle 21. Then the top of the back is forced over and the dropping of the outer end along the tracks 10 serves to raise the opposite end along the tracks 11 with the aid of the initial impetus given by the hand of the operator. When the back is in this position in which it is nearly horizontal the handle latch 15 is operated to lock it there.

The plate carrying frame is then turned on its pivot shaft until the pin 37 engages one of the hooks 52. The continued motion of the plate carrying frame with the plate therein causes the receiver to be tilted on account of this connection into a position to receive the plate on its rollers. In other words the receiver is tilted over to bring the rollers under the straight edges of the swinging stereotype plate held in the plate frame. Upon the reverse movement of the plate carrying frame the compression spring 49 forces the V-shaped cam plate 47 upwardly. This operates on the roller 46 and causes the receiver to turn to its neutral position. As the cast plate turns axially toward the central position the lug h thereon passes by the fixed projection 54 on the receiver and leaves the plate supported by the rollers 44. As these are shown arranged in an inclined plane the weight of the plate will cause it to move along down the plane and into position in the finishing mechanism. It is received therein, against stops as described in my

above mentioned application for patent and thereafter shaved and trimmed after the operator presses down on the treadle 259 on the side of the machine on which he stands. After this it moves on down the incline and into the cooling device which flushes the inner surface of the plate with water. The plate is then removed from the cooler by hand.

It is to be understood of course that the finishing mechanism shown herein is a convenient one for this purpose, being copied from my above mentioned application for patent, but that this invention is capable of being used with many other kinds of finishing devices and is not limited to the gravity conveyer system as any desired kind of conveyer can be used. In fact the same principle can be carried out in a machine in which the plate is conveyed from the receiver to the finishing device by hand. It is to be understood also that the particular type of casting box and means for opening and closing the same are shown for convenience and that the invention is capable of use with practically all types of machines for this general purpose. It is to be understood also that the invention is capable of being carried out with other changes in details of construction, and that it is not limited to the mechanism herein shown and described.

Having thus fully described my invention what I claim is:

1. In a stereotype plate making machine, the combination of a plurality of casting boxes arranged parallel with each other, a common means parallel with said boxes for receiving plates therefrom, and a single finishing mechanism arranged in position to receive the plates directly from said receiving means.

2. In a stereotype plate making plant, the combination of two casting boxes arranged side by side, and a finishing device arranged parallel therewith and in line with a point half way between them and adapted to receive plates from either of them.

3. In a stereotype plate making plant, the combination of a plurality of casting boxes, a receiver arranged in position to receive plates laterally from each of said casting boxes, and a finishing machine in position to receive plates longitudinally from said receiver.

4. In a stereotype plate making plant, the combination with a pair of casting boxes arranged parallel with each other, of a receiver between said boxes for receiving the plates from both of them, and a finishing mechanism arranged at the end of said receiver.

5. In a stereotype plate making plant, the combination of a pair of casting boxes arranged parallel with each other, and a re-

- ceiver between them adapted to receive plates from both of the casting boxes when discharged sidewise therefrom.
6. In a stereotype plate making plant, the combination of a plurality of casting boxes, a receiver arranged adjacent thereto, means for transferring a plate from each of said boxes laterally into the receiver, and a finishing mechanism in position to receive the plates from said receiver.
7. In a stereotype plate making plant, the combination of a pair of casting boxes, a finishing means, and means for transferring the plates laterally from the casting boxes and then longitudinally into the finishing means.
8. In a stereotype plate making plant, the combination of a pair of casting boxes arranged with their axes parallel, a finishing mechanism arranged with its axis parallel with those of the casting boxes, and means for taking plates from each casting box and transferring them into the finishing means.
9. In a stereotype plate casting machine, the combination of a pair of casting boxes arranged side by side, guides for guiding the backs thereof into position to deliver the cast plates, and means between said boxes for receiving the cast plates from either back.
10. In a stereotype plate casting machine, the combination of a pair of upright stationary cores, a pair of movable backs co-operating therewith, guides for guiding said backs into position to deliver the cast plates, and means between said guides for receiving a cast plate from either back.
11. In a stereotype plate casting machine, the combination of a pair of casting boxes, each having a movable member adapted to move to position to deliver a cast plate, and means located between said movable members when in delivering position for receiving the cast plate from either of them.
12. In a stereotype plate casting machine, the combination of a pair of frames arranged side by side, casting boxes supported by said frames, each having a member movable on its frame to delivering position, and a receiver for the cast plate located between said frames but tiltable on a longitudinal axis into position to receive a plate directly from either casting box.
13. In a stereotype plate casting machine, the combination of a pair of casting boxes arranged parallel with each other, a receiver located between the casting boxes, said receiver being mounted to swing on a longitudinal axis, each casting box having a plate delivery frame adapted to swing over into position to deposit a plate on said receiver.
14. In a stereotype plate casting machine, the combination of a pair of casting boxes arranged parallel with each other, a receiver located between the casting boxes and mounted to swing on a longitudinal axis, each casting box having a plate delivery frame adapted to swing over into position to deposit a plate on said receiver, and each having means for engaging the receiver and tilting it toward itself as the frame moves toward the receiver.
15. The combination with two casting boxes, of a receiver, means for transferring cast plates from one casting box to said receiver, means for transferring cast plates from the other casting box to the same receiver, a finishing mechanism in alignment with said receiver, and means for conducting the plates from the receiver to the finishing mechanism.
16. In a stereotype plate casting machine, the combination with a casting box, of a concave frame therein having side bars and semi-circular end bars for supporting a semi-cylindrical plate therein, said frame being mounted to swing on a longitudinal axis at one side of the casting box, and a receiver mounted alongside the casting box adjacent to said axis for receiving a plate directly from said frame as the frame swings away from the casting box, said frame being provided with means for tilting the receiver toward itself as the frame moves outwardly from the casting box.
17. In a stereotype plate casting machine, the combination with a casting box, of a frame therein for supporting a cast plate, said frame being mounted to swing on a longitudinal axis at one side of the casting box, a receiver mounted alongside the casting box adjacent to said axis for receiving a plate directly from said frame as the frame swings away from the casting box, an arm adapted to swing with said frame, and a hook connected with the receiver and in position to be engaged by said arm as it swings outwardly for drawing down the side of the receiver which is adjacent to the casting box as the frame swings outwardly.
18. In a stereotype plate casting machine, the combination with a casting box, of a frame for supporting a cast plate, mounted to swing at one side of the casting box, a receiver for receiving a plate from said frame, an arm adapted to swing with said frame, and a hook connected with the receiver and in position to be engaged by said arm as it swings outwardly for drawing down the side of the receiver which is adjacent to the casting box as the frame swings outwardly.
19. In a stereotype plate casting apparatus, the combination with a casting box, of a receiver alongside thereof mounted on a longitudinal axis, said receiver comprising a series of freely rotatable rolls having flanges thereon for receiving the cast plate from the casting box, and means for tilting the receiver.

the receiver toward the casting box to receive the plate.

20. In a stereotype plate casting apparatus, the combination with a casting box, of a receiver alongside thereof mounted on a longitudinal axis, said receiver comprising a series of freely rotatable rolls having flanges thereon for receiving the cast plate from the casting box, means for tilting the receiver toward the casting box to receive the plate, and means for automatically restoring the receiver to horizontal position after a plate is deposited thereon. 50

21. In a stereotype plate casting apparatus, the combination with a casting box, of a receiver alongside thereof for receiving the cast plate from the casting box, means for tilting the receiver toward the casting box to receive the plate, and means for automatically restoring the receiver to horizontal position after a plate is deposited thereon, the last named means comprising an arm adapted to swing with the receiver and having a roller thereon, and a V-shaped spring-pressed cam centrally located with respect to said receiver for engaging the arm and normally forcing it into the apex of the V to restore to neutral position. 55

22. In a stereotype plate casting apparatus, the combination with the casting box, of a receiver alongside thereof having a series of freely rotatable rolls thereon for receiving the edges of a plate, said rolls being located on an incline, said receiver being adapted to tilt from the inclined position in which it receives a plate to a neutral position, and a fixed stop for preventing the plate from rolling down the incline while the receiver is out of neutral position, said stop being located in a position to be out of registration with the plate when the receiver is in neutral position. 60

23. In a stereotype plate casting apparatus, the combination with the casting box having means for casting a stereotype plate

with a lug on the riser thereof, of a tiltable receiver for receiving the plate from the casting box, means for tilting the receiver toward the casting box to receive the plate, means for restoring the receiver to a neutral position with the plate thereon, and a fixed stop connected with the receiver in position to engage said lug during the motion of the plate from the casting box to the receiver, but to come out of registration therewith when the receiver is in neutral position. 55

24. In a stereotype plate casting apparatus, the combination with a casting box, of a receiver alongside thereof for receiving the cast plate from the casting box, means for tilting the receiver toward the casting box to receive the plate, and means for automatically restoring the receiver to horizontal position after a plate is deposited thereon. 60

25. In a stereotype making plant, the combination of a plurality of casting boxes arranged parallel with each other, a finishing mechanism arranged in position to receive the plates from each of said casting boxes, and a device for transferring plates from each casting box to the finishing means. 70

26. In a stereotype plate making plant, the combination with a number of casting boxes arranged parallel with each other, of a receiver between said boxes, means for transferring plates from each box to the receiver, a finishing mechanism arranged at the end of the receiver, and means for conducting plates from the receiver to the finishing mechanism. 75

In testimony whereof I have hereunto set my hand in the presence of two subscribing witnesses.

CHARLES E. HOPKINS.
